[57] CLAIM

The ornamental design for a belt flashlight, as shown and described.

DESCRIPTION

FIG. 1 is a perspective view of a belt flashlight showing our new design;

FIG. 2 is a reduced top plan view thereof;

FIG. 3 is a front view thereof;

FIG. 4 is a side elevation view thereof, the other side

being a mirror image of this view;

FIG. 5 is a rear view thereof; and,

FIG. 6 is a bottom view thereof.

Fig. 1
